UNITED STATES PATENT OFFICE.

STEVE BOROS, OF AKRON, OHIO.

ELECTRICALLY-OPERATED WALL-PAPER MACHINE.

Application filed January 23, 1928. Serial No. 248,831.

This invention relates to a wall paper handling machine, the general object of the invention being to provide means for unrolling the paper, applying paste to the under side 5 thereof and for trimming the edges of the paper as it is being unrolled.

A further object of the invention is to provide a conveyor on which the unrolled and pasted paper lies, so that it can be easily 10 picked up by the paperhanger.

A still further object of the invention is to provide adjustable cutting means for reducing the width of the paper, with a handle for moving said cutting means into operative 15 position.

This invention also consists in certain other features of construction and in the combination and arrangement of the several parts, to be hereinafter fully described, illustrated in 20 the accompanying drawings and specifically pointed out in the appended claims.

In describing my invention in detail, reference will be had to the accompanying drawings wherein like characters denote like or 25 corresponding parts throughout the several views, and in which:—

Figure 1 is an elevation of the device.

Figure 2 is a plan view thereof.

Figure 3 is an end view thereof.

Figure 4 is a section on line 4—4 of Figure 2.

Figure 5 is a section on line 5—5 of Figure 4.

Figure 6 is an enlarged sectional view 35 through the motor carrying end of the machine.

Figure 7 is a detail view showing a pair of the trimming knives.

In these views, the numeral 1 indicates an 40 upright frame for supporting the various parts of the device and 2 indicates a platform arranged at one side of the frame upon which the operator may stand. The uprights of the frame are provided with rollers 3 so that the device can be rolled from one place to another.

A shaft 4 has its ends placed in the bayonet 50 slots 5, one of the slots being arranged in each side of the machine, this shaft being adapted to carry the roll of wall paper which is indicated at A. A disk 6 is adjustably and removably arranged on the shaft through means of the collar 7 which is held to the shaft by a set screw 8, a coil spring 9 being placed on the shaft between the collar and disk so as to press the disk against

the roll of paper. This disk is used when a short roll of paper is placed on the shaft. The shaft is removably supported by the frame through means of the bayonet slots 60 so that it can be lifted from the frame and a roll of paper placed thereon. A flat bar 10 extends across the frame in front of the roll of paper and forms a guide for the paper leaving the roll. 65

A roller 11 is supported by pintles for rotary movement in the frame and a conveyor belt 12 passes over this roller. The belt also passes over a roller 13 arranged at the opposite end of the machine and idle rollers 14 70 are placed intermediate the rollers 11 and 13, at the top of the frame, for supporting the upper reach of the belt. A belt tightener 15 is pivoted to the top part of the frame adjacent the roller 13 and has its 75 roller 16 engaging the lower reach of the belt. A small roller 17, formed of metal, has its ends placed in the notches 18 formed in the sides of the frame and acts to press the paper against that part of the belt passing over the 80 top of the roller 11 so that the movement of the conveyor belt will act to draw the paper from the roll A.

A cylindrical casing 19 is supported in the frame adjacent the roller 11, the lower part 85 of the casing forming a paste chamber 20 which is provided with a drain 21 in its bottom which is controlled by a valve 22.

A brush roller B is rotatably mounted in the casing, with the brushes arranged to dip 90 into the paste in the paste chamber as the roller revolves and the top part of the casing has an opening 23 therein through which the paper is pressed against the bristles of the brushes by a roller 24, preferably formed of wood and which has its pintles engaging the notches 25 formed in the sides of the frame. Idle rolls 26 are placed one on each side of the roller 24, over which the paper passes as it enters and leaves the opening. 95

The brush roller is composed of the tubular sections 27, the outer ones of which are of larger diameter than the central one, the brushes 28 which have socketed stems 29 on their inner faces engaging the sockets 30 in the outer sections 27, the interiors of the stems being threaded for engagement with the threaded stub shafts 31 journaled in the parts of the outer sections which carry the sockets 30 and the inner ends of these stub shafts carrying the bevel gears 32 which mesh with the bevel gears 33 on a shaft 34 100 105 110

which passes through the sections 27, with one end projecting beyond a side of the frame to receive a handle 35. Thus by turning the shaft by means of its handle, the brushes will be adjusted outwardly or inwardly, as desired.

A shaft 36 extends across the frame with its ends journalled in the side pieces thereof, said shaft being arranged between the brush 10 roller and the roll of paper. A pair of disk cutters 37 are fastened to this shaft, one adjacent each end thereof. A stub shaft 38 is journalled in each side piece of the frame under the shaft 36, and the inner end of said 15 stub shaft carries a disk cutter 39 which operates with the cutter 37 to trim an edge off the paper. The rear end of the shaft 37 carries a gear 40 which meshes with a gear 41 on the stub shaft 38 and a gear 42 is arranged on 20 the outer end of the other stub shaft and meshes with a gear 43 on the front end of the shaft 36. A sprocket wheel 44 is arranged on one of the pintles of the brush roller B and a chain 45 passes over this sprocket wheel and 25 over a small sprocket wheel 46 attached to the shaft of an electric motor M which is supported from the frame. An idle gear 47 meshes with a pinion 48 attached to the pindle of the brush roller adjacent the sprocket 44 30 and this gear 47 meshes with the gear 42. Thus the cutters are rotated from the brush roller. An idle gear 49 meshes with the pinion 48 and with a gear 50 which is attached to one of the pintles of the roller 11 so that 35 this roller 11 is also rotated from the brush roller.

A third cutter disk 51 is adjustably and removably connected with the shaft 36 through the set screw 52 and a shaft 53 having a plurality of annular grooves 54 therein 40 is arranged under the shaft 36 and is carried by the arms 54' which are pivotally connected with the sides of the frame, as shown in Fig. 6. A handle 56 is attached to one of the arms 45 for raising and lowering the shaft 53 to press the paper against the cutter 51 which acts to reduce the width of the paper. A projection 57 is attached to one of the arms 50 and a stop 58 is provided for engagement by said projection for limiting the downward movement of the arms and the shaft 53.

From the foregoing it will be seen that as the paper is drawn off the roller A by the movement of the conveyor, it will first pass 55 between the cutter disks so that its edges are trimmed and then it passes under the roller 24 which presses it against the rotating brushes, which act to coat the under face of the paper with paste. The paper then passes 60 upon the conveyor from which it can be picked up by the paperhanger. When a strip of paper of narrow width is needed, the knife 51 is adjusted on the shaft 36 and then the handle is moved to raise the grooved 65 roller 53, which will press the paper against

the knife, it being understood that the knife will enter one of the grooves in the roller so that its cutting edge is not dulled by coming in contact with the roller. The part of the strip being cut by the knife 51 which is not 70 to be used, is not carried through the pasting mechanism, but is allowed to drop from the roller 53, as shown at a in Figure 6.

As will be seen, all the movable parts are operated from the electric motor and that any 75 length of paper roller may be placed on the shaft 4 by adjusting the disk 6 thereon or entirely removing said disk. It will also be seen that the brushes can be easily adjusted outwardly when they become worn by turning the shaft 34 through means of the handle 35. The paste chamber can be easily drained by opening the valve 22 and then water can be poured in the chamber to clean the same 80 and the brushes and then this water can be drained from the chamber by opening said valve 22.

Figure 4 shows a block 59 extending across the frame adjacent the roller 11 and under which the belt passes, the paper being adapted to pass over the block so that it can be cut by running a knife along that part of the paper resting on the block. The block is provided with a groove 60 to facilitate the 95 knife cutting the paper.

It is thought from the foregoing description that the advantages and novel features of my invention will be readily apparent.

It is to be understood that I may make 100 changes in the construction and in the combination and arrangement of the several parts, provided that such changes fall within the scope of the appended claims.

What I claim is:

1. A wall paper handling machine comprising a supporting frame, a conveyor thereon, a paper roll holding shaft removably supported in the frame, means for pressing the paper against the conveyor to cause the conveyor to pull the paper from the roll, means 105 for applying paste to the paper before it reaches the conveyor, means for trimming the edges of the paper, an electric motor for operating the paste applying means, the conveyor and the trimming means, the paste applying means comprising a rotary brush, a cylinder surrounding the same and having an opening in its upper end, a roller for pressing the paper into the opening against the brush, a paste chamber at the lower end 110 of the cylinder into which the bristles of the brush dip, said rotary brush comprising a plurality of bristle carrying parts, a rotary member carrying the brush parts and manually operated means for adjusting the brush 115 parts radially.

2. A wall paper handling machine comprising an upright frame, a cylinder adjacent one end of the frame having an opening 120 in its top and its lower part shaped to form 125

- a paste receiving chamber, a valved drain for said chamber, a rotary brush in said cylinder, an electric motor in the frame, means for driving the brush from said motor, a conveyor consisting of two rollers journaled in the frame and a belt passing over the rollers, one roller being arranged adjacent the cylinder, means for driving said roller from the brush, means for supporting a roll of paper 5 at one end of the frame, a roller mounted in the frame for vertical movement for pressing the paper into the opening in the cylinder so that the paper will be engaged by the bristles of the brush, guiding rollers carried by the frame adjacent the movable roller, a weighted roller supported in the frame for vertical movement for pressing the paper against a 10 part of the conveyor belt, a knife carrying shaft journaled in the frame, a cutter disk arranged adjacent each end of said shaft, a stub shaft journaled in each side of the frame under the shaft just mentioned, a cutter disk carried by each stub shaft and cooperating with the cutter disk on the other shaft to trim the edges of the paper, means for rotating the cutter shafts from the brush, a third cutter disk on the shaft which carries the two 15 cutter disks, means for adjusting said third cutter disk on the shaft, a roller provided with transverse grooves, arms pivoted to the sides of the frame for supporting the roller, and a handle for raising the arms and roller to cause the roller to press the paper against the third cutter. 20
3. A wall paper handling machine comprising an upright frame, a cylinder adjacent one end of the frame having an opening in its top and its lower part shaped to form a paste receiving chamber, a valved drain for 25 said chamber, a rotary brush in said cylinder, an electric motor in the frame, means for driving the brush from said motor, a conveyor consisting of two rollers journaled in the frame and a belt passing over the rollers, one roller being arranged adjacent the cylinder, means for driving said roller from the brush, means for supporting a roll of paper 30 at one end of the frame, a roller mounted in the frame for vertical movement for pressing the paper into the opening in the cylinder so that the paper will be engaged by the bristles of the brush, guiding rollers carried by the frame adjacent the movable roller, a weighted roller supported in the frame for vertical movement for pressing the paper against a 35 part of the conveyor belt, a knife carrying shaft journaled in the frame, a cutter disk arranged adjacent each end of said shaft, a stub shaft journaled in each side of the frame under the shaft just mentioned, a cutter disk carried by each stub shaft and cooperating with the cutter disk on the other shaft to trim the edges of the paper, means for rotating the cutter shafts from the brush, a third cutter disk on the shaft which carries the two 40 cutter disks, means for adjusting said third cutter disk on the shaft, a roller provided with transverse grooves, arms pivoted to the sides of the frame for supporting the roller, a handle for raising the arms and roller to cause the roller to press the paper against the third cutter, and a cross bar supported by the frame adjacent the forward end of the conveyor and under which the conveyor belt passes and over which the paper passes so 45 that a knife can be drawn across the paper above the bar to sever the paper. 50

In testimony whereof I affix my signature.

STEVE BOROS.
